(57) **CLAIM**

The ornamental design for a motor car body, as shown and described.

DESCRIPTION

FIG. 1 is a front elevational view of a motor car body showing my new design;

FIG. 2 is a right, front perspective view thereof;

FIG. 3 is a top plan view thereof;

FIG. 4 is a rear elevational view thereof;

FIG. 5 is a right, rear perspective view thereof;

FIG. 6 is a right side elevational view thereof with the convertible top in downward position;

FIG. 7 is another right side elevational view thereof with the convertible top in upward position;

FIG. 8 is a left side elevational view thereof with the convertible top in downward position; and,

FIG. 9 is another left side elevational view with the convertible top in upward position.

The portions of the motor car body shown in broken lines are for environmental and illustrative purposes and form no part of the claimed design.
